UNITED STATES PATENT OFFICE.

JESSE SINCLAIR, OF DAVENPORT, IOWA.

IMPROVED ANIMAL-SHOEING STOCK.

Specification forming part of Letters Patent No. 36,920, dated November 11, 1862.

To all whom it may concern:

Be it known that I, JESSE SINCLAIR, of Davenport, in the county of Scott and State of Iowa, have invented a new and Improved Animal-Shoeing Stock; and I do hereby declare that the following is a full, clear, and exact description of the same, reference being had to the accompanying drawings, making part of this specification, in which my invention is embodied in a stock represented by a perspective view.

The invention consists, first, in the combination of the lifting bars and belly and back girts with the cords, windlasses, and actuating mechanism.

It consists, secondly, in an arrangement of parts for supporting the animal's foot while the shoe is being fitted and nailed, and also while the foot is being dressed, all as will be hereinafter fully explained.

To enable others skilled in the art to fully understand and use my invention, I will proceed to describe its construction and operation.

The stock proper is composed of uprights A, string-pieces B, cross-pieces C, and sills D, which are all put together by mortise-and-tenon-joints in the usual mode of joinery. The sills D are connected together by ties E, of the same size, and with them constitute the foundation of the stock, the space inside of the sills and ties being boarded over, and thus a floor is formed for the animal to stand upon while the girts are being adjusted to his body. The frame or stock at top is strengthened by arched metallic braces a, and bottom by inclined wooden braces b, the latter being furnished with tenons on their ends adapted to fit corresponding mortises in the sills and uprights, respectively.

F F' are two windlasses, supported parallel with each other on top of the frame in boxes c c', in which they are fitted to revolve. These boxes are secured to the upper side of the end cross-pieces C. The windlass F is provided with a winch, m, and on its opposite end with a gear-wheel, n, which latter gears into a wheel, o, of the same size on the same end of the windlass F'. Power being applied to the winch, the two windlasses being geared together they are caused to move simultaneously and with equal velocity in opposite directions.

G G' are metallic lifting-bars, suspended by

cords d from the windlasses F F', respectively, and fitted at their ends and in the middle in box-brackets e, within which they have vertical movement only.

H are foot-rests, which in the present instance are formed on one end of short shafts f, which terminate at their opposite ends in levers g. The short shaft f of each foot-rest H, is nearly double the length of the box h, in which it is fitted to rotate, so as to be capable of longitudinal movement therein, for the purpose hereinafter to be explained. The boxes h are attached to the back side of the upright A. The foot-rests on one side are fashioned to conform to the ankle and on the opposite side to the sole of the hoof of the animal, so that by turning the rest in one direction it answers to support the foot of the animal while his shoes are being set, and by turning in the reverse direction to support the foot while the hoof is being dressed.

L are arms provided on one side with a number of fixed rings, i, which are placed in a line equidistant apart on the arm, and serve to confine the lever g to lock the foot-rest when properly adjusted. The arms L are each attached to the sill-pieces D by a pivot, j, on which they are permitted to swing laterally.

I I' are girts attached at their ends by staples to the standards at the front and rear end of the stock, respectively. J J' and K K' are similar girts, attached at their ends to the string-pieces B and lifting-bars G G', respectively, the former by staples and the latter by metallic hooks k on the ends of the straps or girts, and catching over the bars.

The girts being all unbuckled, so as to leave an unobstructed entrance into the stock, the animal is led therein and hitched. The straps I I' at the front and back ends are then buckled up, and the girts J J' K K' properly adjusted around the body. If it is desired to shoe more than one foot at a time the animal must be lifted off of his feet or elevated from the floor. This is effected, after the girts are properly adjusted, by winding the cords by which the lifting-bars are suspended upon the windlasses. The foot-rest is now turned down in front of the foot it is desired to examine or work upon, and the foot fastened by a strap, M, encompassing the ankle, after which the foot is raised by pressing down on the lever g. When the foot is raised to the proper height to work at,

the arm L is moved toward the end of the lever g of the rest, so as to have its end enter one of the fixed rings i, whereby the foot-rest is prevented from dropping down until intentionally released. The shoe being fitted and nailed, the foot is released and the rest turned down, so as to allow the foot to hang down if the animal be suspended, or rest on the floor if otherwise. The rest is now drawn to one side by slipping the shaft in its box and placed behind the foot when it (the foot) is raised and held as before until the hoof is dressed.

The above invention is more especially designed for shoeing vicious or fractious horses and mules, though it is equally well adapted as the common stock for shoeing oxen.

Having thus described my invention, what I claim as new, and desire to secure by Letters Patent, is—

1. The lifting-bars G and girts J J' and K K', in combination with the cords d, windlasses F F', gear-wheels n o, and winch m, when arranged to operate in the manner and for the purpose specified.

2. The foot-rest H, shaft f, and lever g, in combination with the arm L and rings i, when arranged to operate in the manner specified.

JESSIE SINCLAIR.
